[57] CLAIM

The ornamental design for a cage for animals, as shown and described.

DESCRIPTION

FIG. 1 is a perspective view taken from the top, front and left side of a cage for animals showing my new design;

FIG. 2 is a front elevational view thereof, the rear being the same as the front shown;

FIG. 3 is a top plan view thereof;

FIG. 4 is a right side elevational view thereof, the left side being the same as the right side shown;

FIG. 5 is a bottom plan view thereof;

FIG. 6 is a cross sectional view taken on line 6—6 of FIG. 3; and

FIG. 7 is an exploded perspective view thereof showing the cage partially disassembled.
